UNITED STATES PATENT OFFICE.

FRANK A. PULHEMUS, OF HOPKINS STATION, MICHIGAN, ASSIGNOR OF
ONE-HALF TO LUCIUS D. HARRIS, OF GRAND RAPIDS, MICHIGAN.

PRINTING-PRESS.

SPECIFICATION forming part of Letters Patent No. 593,164, dated November 2, 1897.

Application filed October 28, 1896. Serial No. 610,356. (No model.)

To all whom it may concern:

Be it known that I, FRANK A. PULHEMUS, a citizen of the United States, residing at Hopkins Station, in the county of Allegan 5 and State of Michigan, have invented certain new and useful Improvements in Printing-Presses, of which the following is a specification.

My invention relates to improvements in bed and cylinder presses; and its objects are, first, to provide a light, easy-running, and convenient cylinder-press that may be conveniently run by hand-power, and, second, to provide means to prevent the cylinder from 10 pressing upon the naked type when passing back over the form after having discharged the printed paper. I attain these objects by the mechanism illustrated in the accompanying drawings, in which—

20 Figure 1 is a side elevation of my press. Fig. 2 is a plan of the same with the paper-stand removed to show the inking-rolls and table. Fig. 3 is a plan of the adjusting-shaft and eccentrics; and Fig. 4 is a sectional end 25 view of the cylinder resting on the top rail of the frame, illustrating the manner of actuating the fingers that secure the paper to the cylinder.

Similar letters refer to similar parts throughout the several views.

30 My press is mounted upon a supporting-frame A, and at each side of this frame I pivot a toothed track B to the plate, as at b. The opposite ends of these tracks are supported on the eccentrics j', said eccentrics being mounted on the shaft J² in such a manner that when the cylinder C is carried to the position indicated at c' its rim C' comes in contact with the lever J and throws the eccen- 35 trics over in position to raise this end of the tracks sufficiently so that when the cylinder returns to the position indicated at c" it will be entirely above the type-form and move clear of the type E, thus averting the danger 40 of marring the type and injuring the printing.

45 The cylinder C is made substantially of the form shown in Fig. 1, having at each end a gear-wheel C², fitted to mesh freely with the gear-teeth on the tracks B, so that 50 the cylinder cannot be made to deviate from its proper course or position and the fingers

c will always be in the proper position when the cylinder is at c' or the position shown in Fig. 2 to receive the paper from the paper-stand I and place it properly on the form E 55 for printing. Outside of these gear-wheels, at each end, I place a flange C', which acts a double purpose—first, to engage with the levers H, J, and J' in the manner and for the purpose hereinafter more fully set forth, and, 60 second, to act as a convenient handhold with which to manipulate the cylinder. The lever J is connected to the lever J' by the connecting-rod j in such a manner that the flange C' of the cylinder when passing from c' to c" 65 will throw the lever J' to the position shown in Fig. 1 and with it the lever J to its corresponding position, as shown by the solid lines in said figure, and by this means carry the eccentrics from under the tracks B, so that 70 the return of the cylinder will be so close to the surface of the type-form E as to insure a perfect imprint of the type on the paper.

75 My appliance for operating the fly F consists of the gear-wheels G and G', so arranged that the turning of the wheel G will turn the wheel G' and throw the fly to the positions necessary to receive the papers from the cylinder and deposit them on the receiving-table. This action is achieved by the use of 80 the lever H, which is connected with the arm g on the wheel G by means of the connecting-rod h. The lever H is pivoted near its longitudinal center to the frame A, and the connecting-rod h is attached below this point, so that 85 the motion of the upper end of the lever is transmitted to the arm g in the reverse direction. At the upper end of the lever I form a concave T-arm H' in position so that the flange of the cylinder C' when passing over it will 90 throw it in the direction that the cylinder is moving, so that when the cylinder is moving toward c' the lever will be carried over to the position indicated by the dotted lines and the fly is thrown to the position indicated by its 95 dotted lines in Figs. 1 and 2 just in time to pass the cylinder and receive the paper as it passes over it, and the reverse motion of the cylinder will carry it back to the position indicated by the solid lines to carry the paper 100 to the receiving-table.

The inking-rolls D are connected with the

cylinder or cylinder shaft somewhat as indicated in Figs. 1 and 2 by connecting-rods so that they will be actuated by the movements of the cylinder to pass from the inking-pad 5 K to the printing-form E, and vice versa.

The fingers c are actuated by any ordinary device that may be made available for the purpose—as, for instance, the lever c' in passing over the beads a' upon the top rail of the 10 frame. (See Fig. 4.)

The paper-stand I may be supported on standards i.

P represents the paper passing to the cylinder, and h' is a stop for the lever H.

Having thus fully described my invention, what I claim as new, and desire to secure by Letters Patent of the United States, is—

1. In a printing-press, a supporting-frame, a track pivoted at one end to one end of each 20 side of the supporting-frame, a shaft having an eccentric at each end in position to actuate the free end of the tracks vertically, a lever attached to said shaft in position to be actuated by the cylinder, a lever at the other 25 end of the machine connected with said lever and in position to be similarly actuated by the cylinder but in the opposite direction, a lever pivoted to the side of the frame, a T-arm across the top of said lever in position to

be actuated by the flange of the cylinder in 30 either direction, a connecting-rod passing from said lever to a gear-wheel at the foot of the press, a small gear meshing with said gear, a fly secured to the shaft supporting said small gear so that the motion of the lever is utilized to actuate the fly to and from the cylinder, a cylinder arranged to actuate the several levers, to receive, print and discharge papers and inking appliances connected to act with said cylinder, substantially as 40 and for the purpose set forth.

2. The combination, with a frame, an impression-cylinder, a form and adjustable carrying-tracks; of a fly pivoted at one end of the frame, a gear and rack attached to actuate 45 said fly, and a lever centrally pivoted to the frame, a T at its upper end in position to receive the moving cylinder and transmit its motion to the lower end in a reverse direction and thence, by means of a connecting-rod to 50 actuate the fly gear and rack, substantially as and for the purpose set forth.

Signed at Hopkins Station, Michigan, October 17, 1896.

FRANK A. PULHEMUS.
